UNITED STATES PATENT OFFICE

JOHN F. MOCK, OF PHILLIPSBURG, NEW JERSEY, ASSIGNOR TO INGERSOLL-RAND COMPANY, OF JERSEY CITY, NEW JERSEY, A CORPORATION OF NEW JERSEY

CENTRALIZER FOR DRILL STEELS

Application filed November 2, 1927. Serial No. 230,552.

This invention relates to rock drills, but more particularly to a centralizer adapted to be supported by a rock drill shell and forming a bearing for the free end of the 5 drill steel.

One object of the invention is to maintain the cutting bit of the drill steel in axial alignment with the rock drill, particularly when starting a new drill hole in a rock face.

Another object of the invention is to simplify the construction and reduce the cost of maintenance of centralizers of this type.

Other objects will appear hereinafter and to all of these ends the invention consists of 15 the combination of elements and arrangements of parts substantially as hereinafter described and claimed and illustrated in the accompanying drawings, in which

Figure 1 is an elevation of the front end 20 of a rock drill and its shell, illustrating the manner in which the centralizer supports and guides the drill steel,

Figure 2 is a transverse view taken through Figure 1 on the line 2—2 looking in the direction indicated by the arrows, and

Figure 3 is an enlarged side elevation of the centralizer.

Referring more particularly to the drawings, A represents a shell of any suitable type having a conical projection B whereby the shell may be secured to a column or other suitable support for holding the shell in fixed position with respect to the working surface, such as the rock C.

In the present instance, only the front end 35 of a rock drill front head D is shown in the drawings for the sake of simplicity of illustration, but it is to be understood that other elements (not shown) of the rock drill may cooperate slidably with guideways E of the shell A in a well known manner. A working implement F illustrated in this instance as a drill steel extends with its rearward end into the front head D to receive the 40 blows of a reciprocatory hammer piston (not shown) of the drill.

In certain drilling operations, it is at times found difficult to maintain the drill bit in axial alignment with the rock drill whereby 45 the drill steel is being actuated, particularly

when the rock drill lies in a horizontal or an inclined position. After a certain period of usage wear is caused in the chuck parts of the rock drill and as a result the bit end of the drill steel tends to decline from the 55 axis of the rock drill. Such declination of the drill steel is accentuated by wear on these parts, although when new, this tendency is also present due to the looseness of the fit between the shank of the drill steel and the 60 drill chuck. Owing to these conditions the drill bit will describe a gyratory movement about its axis when starting a new drill hole. As a result the drill hole will decline from the intended course. Quite frequently these 65 conditions are not detected until a certain depth has been drilled or until drill steels of greater length have been substituted for the starting steel. This condition requires an interruption in the drilling operation to adjust 70 the rock drill to a position which will coincide with the course of the drill hole, otherwise the drill steel will bind in the drill hole and will greatly hinder the efficient operation of both the percussive element and the rotation mechanism. Moreover, if the drill steel 75 is not maintained substantially coaxial with the rock drill, it will be difficult to maintain the gauge of the drill bit and the drill steel will require more frequent sharpening than 80 would be the case were the drill steel held in axial alignment with the chuck mechanism of the rock drill.

The present invention aims to eliminate the foregoing described unfavorable features 85 and to this end a centralizer designated by G is disposed about the drill steel F to form a bearing therefor near the front end of the drill steel. The centralizer G comprises a pair of arms H and J both of which have 90 lateral extensions K at their lowermost ends to extend slidably into the guideways E of the shell A.

In the inner or adjacent surfaces L of the arms H and J are formed semi-circular 95 grooves O for the reception of bushings P. The bushings P are in this instance also of semi-circular form and are adapted to contact with each other when in the operative position about the drill steel F. The bush- 100

ings P seat loosely in the grooves O so that the said bushings and the arms are capable of some relative rotative movement.

Suitable means are provided for maintaining the bushings P in the arms H and J. These means in the present instance consist of lateral lugs Q which extend through transverse apertures R in the arms H and J. The lateral lugs Q preferably extend with their free ends beyond the apertures R to enable the free ends of said lugs to be upset to form projecting portions S which may cooperate with the side of the arms H and J to prevent accidental withdrawal of the bushings from the said arms.

To the end that a certain pivotal movement may be obtained between the bushings P and the arms H and J the apertures R are preferably of somewhat larger cross sectional area than the lugs Q. In this way the bushings P will be free to adjust themselves to the same operative position irrespective of the width of the shell in which the centralizer may be disposed.

Means are provided for drawing together the uppermost ends T and U of the arms H and J and thus also to force the lateral extensions K into and maintain them in engagement with the guideways E of the shell A. These means in the present instance consist of a T-shaped latch in the form of a bolt V which extends through an aperture W in the arm H and through a slot X in the arm J. The bar or head Y of the bolt V preferably bears against the side of the arm H and a nut Z is threaded on the opposite end of the bolt V to bear against the side of the arm J.

In assembling the centralizer a bushing P may be placed in each of the arms H and J and the projecting ends of the lugs Q may then be upset in the manner described. After the bolt V has been placed in the arms the centralizer will be in readiness to be disposed about the drill steel F. This may be accomplished by either inserting the drill steel between the arms or, if the drill steel be of the type which is equipped with a collar or lugs or other equivalent means for preventing its ejection from the front head, the nut Z may be unscrewed a sufficient distance on the bolt to enable the arms H and J to be spread to a distance which will enable the drill steel F to be inserted between the surfaces L of the arms.

After the centralizer has been disposed in the guideways E of the shell the nut Z may be tightened in the direction necessary to both move the lateral extensions K outwardly and force them into the guideways E and also to force the adjacent surfaces of the bushings P firmly into contact with each other. By turning the nut Z down tightly against the arm J the lateral extensions K may be forced into the guideways E to such an extent that the centralizer may only be

removed by again relieving the pressure of the nut Z. Ordinarily however, it is desirable that only sufficient friction should exist between the guideways E and the lateral extensions K to prevent the centralizer from being shaken out of the shell by the vibrations and shocks incident to drilling. When so adjusted the centralizer may be readily displaced by the front end of the front head D as said front head approaches the front end of the shell A. The centralizer will be gradually pushed out of the guideways E and may then be removed from the vicinity of the drill hole without interrupting the drilling.

I claim:

1. A centralizer for drill steels, comprising a pair of arms forming a guide for a drill steel, means integral with one end of the arms adapted to cooperate slidably with the guideways of a rock drill shell, and means acting on the other ends of the arms to draw the last mentioned ends together for pressing the first said means laterally outward into engagement with such guideways.

2. A centralizer for drill steels, comprising a pair of arms, bushings in the arms adapted to encircle a drill steel and seating loosely in the arms, lateral extensions on corresponding ends of the arms to cooperate slidably with the guideways of a rock drill shell, and means acting on the other ends of the arms for pressing the bushings into contact with each other and for forcing the lateral extensions into engagement with such guideways.

3. A centralizer for drill steels, comprising a pair of arms having transverse apertures, semi-circular bushings in adjacent sides of the arms forming a bearing for a drill steel, lateral lugs on the bushings extending loosely through the apertures, upset portions on the lugs cooperating with the arms to maintain the bushings in the arms, lateral extensions on corresponding ends of the arms to extend into the guideways of a rock drill shell, and means including a bolt and nut acting on the other ends of the arms for pressing adjacent faces of the bushings firmly into contact with each other and for maintaining the lateral extensions in frictional engagement with such guideways.

4. A centralizer for drill steels, comprising a pair of arms having transverse apertures, semi-circular bushings in adjacent sides of the arms forming a bearing for a drill steel, lateral lugs on the bushings extending through the apertures, said lugs being of smaller cross-sectional area than the apertures to permit limited rotation of the bushings with respect to the arms, upset portions on the free ends of the lugs cooperating with the arms to maintain the bushings in the arms, lateral extensions on corresponding ends of the arms to extend into the guide-

ways of a rock drill shell, and means including a bolt and nut acting on the other ends of the arms for pressing adjacent faces of the bushings firmly into contact with each other and for maintaining the lateral extensions in frictional engagement with such guideways.

5 In testimony whereof I have signed this specification.

JOHN F. MOCK.
